UNITED STATES PATENT OFFICE.

CHARLES E. HUSTED, OF BRIDGEPORT, CONNECTICUT.

DESIGN FOR A BUSINESS-WAGON BODY.

SPECIFICATION forming part of Design No. 16,925, dated October 5, 1886.

Application filed October 17, 1885. Serial No. 180,213. Term of patent 7 years.

To all whom it may concern:

Be it known that I, CHARLES E. HUSTED, a citizen of the United States, residing at Bridgeport, in the county of Fairfield and State of Connecticut, have invented and produced a new and original Design for Business-Wagons; and I do hereby declare the following to be a full, clear, and exact description of the invention, such as will enable others skilled in the art to which it appertains to make and use the same.

Reference is had to the accompanying drawing, forming a part of this specification, which shows a side elevation of my newly designed business-wagon body.

The leading feature of my design consists in open-work sides projecting upwardly from

the body, with plates and platters appearing against the open-work background.

A is the body of the wagon; B, the open-work sides, while the other features of my design are represented by plates C and platters D.

I claim—

The design for a business-wagon body, as herein shown and described, the same consisting of a body, A, having thereon the open-work background B, the latter showing upon its outer face the plates C D.

In testimony whereof I affix my signature in presence of two witnesses.

CHARLES E. HUSTED.
